UNITED STATES PATENT OFFICE.

THOMAS S. DIETLE, OF PAWHUSKA, OKLAHOMA.

WELL-DRILLING APPARATUS.

Application filed October 14, 1926. Serial No. 141,537.

This invention relates to well drilling apparatus and more particularly to the construction of the band wheel and its connections through the usual mechanisms with the drilling string.

An important object of the invention is to provide a construction whereby the speed of operation is materially increased, thus permitting the use of an internal combustion engine instead of the usual steam engine now employed and in which the lag ordinarily caused by the braking effect of the engine against the action of the tools in descending into the hole is eliminated.

15 A further object of the invention is to provide a band wheel construction which may be so connected with its crank that at times when the crank is under a lifting strain, the band wheel is firmly connected therewith to 20 rotate the same, while, when the lowering operation starts, the band wheel is automatically disconnected, so that the crank may move at its own speed, as controlled by the weight of the tool string with which it 25 is operated.

30 A further object of the invention is to provide a structure of this character whereby the band wheel may be thus connected, regardless of the direction of rotation thereof and whereby the band wheel, if desired, can be fixed to the drive, so that the braking action of the engine may be employed.

These and other objects I attain by the construction shown in the accompanying 35 drawings, wherein for the purpose of illustration is shown a preferred embodiment of my invention and wherein:

Figure 1 is a side elevation of well drilling apparatus construction in accordance 40 with my invention;

Figure 2 is a vertical sectional view showing the clutch arrangement;

Figure 3 is a fragmentary plan view showing the clutch control mechanism;

45 Figure 4 is a detail sectional view showing the manner of retaining the clutches in inoperative position;

Figure 5 is a section on the line 5—5 of Figure 2.

50 Referring now more particularly to the drawings, the numeral 10 generally designates a band wheel shaft, 11 a band wheel carried thereby and driven by a belt 12 from an engine 13. The band wheel shaft has a

55 crank 14 to which may be adjustably connected one end of a pitman 15, the opposite

end of which engages one end of a walking beam 16 from the opposite end of which the wire line 17 supporting the tool string is suspended.

In accordance with my invention, the band wheel 11 is rotatably mounted upon the shaft being clamped between a flange 16 formed upon one side of a hub 17 rotatably engaged with the shaft. At the opposite face of the band wheel from the flange 16, a plate 18 is disposed which is clamped to the flange 16 by bolts 19 extending through the band wheel. Both the flange 16 and plate 18 are provided upon their outer faces with ratchets 20, these ratchets facing in opposite directions. Abutting opposite ends of the hub 17 and keyed to the shaft 10 are sleeves 20', the exterior faces of which are preferably hexagonal in form, for a purpose presently to appear.

The outer ends of these sleeves have outstanding collars or flanges 21 against which abut the outer ends of the springs 22 surrounding the sleeves and having their inner ends abutted against clutch collars 23 which have a sliding fit upon the faces of the sleeves. The inner faces of the clutch collars 23 have ratchet teeth 24 matching the ratchet teeth of the ratchet 20 with which they are associated.

The band wheel shafts are usually mounted between upright standards 25, the upper ends of which are provided with bearings 26 for the shaft. In each of the supports 25, I mount a bolt 27 having in its outer end an eye 28 to which is pivoted the lower end of a shifting yoke 29, the arms of which extend to opposite sides of the associated clutch element 23 and are provided with pins 30 operating in grooves 31 formed in the clutch elements.

The upper ends of the arms of the yoke are connected through a link 32 to the short arm 33 of a bell crank lever mounted upon a pivot 34 supported from the associated post 25. The long arm 35 of the bell crank lever has connected thereto a control handle 36 which is led to a convenient point in the derrick structure and there directed through a latch yoke 37 secured to an upright post. The handle portion has a notch 38 receiving one arm 39 of the yoke when the handle is positioned to disengage the associated clutch.

In the use of the device, where it is desired to make the drilling operation as rapid as possible and to employ the entire

force of the tools, one of the clutch elements 23 is permitted to engage, the clutch elements selected, depending upon the direction of rotation of the band wheel. It will be obvious that so long as the band wheel is rotating at a greater speed than the shaft, the clutch will cause the rotation of the band wheel to be transmitted to the shaft, but as soon as the speed of the shaft exceeds that of the band wheel, the shaft will be released and may move independently of the band wheel. It will also be obvious that the tremendous weight of the tools employed in well drilling operations will cause the tool bearing end of the walking beam 16 to move downwardly very rapidly just as soon as the lifting operation is completed and the return stroke is started. This motion will be transmitted through the pitman 15 to the crank 14 and so to the shaft, with the result that during each rotation of the shaft, after the tools have been lifted to the fullest extent to which the crank may lift them, the crank may free itself, permitting the tools to drop and exert their entire force against the bottom of the well. This results not only in a more efficient drilling operation by the tools but in a reduction of the time required for a given number of strokes of the tools, for it will be obvious that the tools will cause the crank to advance much more rapidly than it is possible to advance it with the band wheel and thus, instead of employing only one-half of the rotation of the band wheel for a lifting operation, substantially the entire rotation of the band wheel is employed in this manner. Furthermore, since the return of the clutches is instantaneous in its action, the band wheel will tend to pick up the load of the tools instantly and thus take advantage of any tendency to rebound on the part of the tools. If it is desired that the braking action of the engine be employed, or that the crank be fixed to the band wheel for any reason, this may be accomplished by simultaneously engaging both clutch elements 23.

It will be obvious that the construction

hereinbefore set forth is capable of a certain range of change and modification without materially departing from the spirit of the invention and I accordingly do not limit myself to such specific structure except as hereinafter claimed.

I claim:—

1. In combination with the band wheel shaft of well drilling apparatus having the usual crank for raising and lowering the drilling tools, a band wheel rotatably mounted upon said shaft and a pair of spring pressed ratchet clutches for connecting said band wheel to the shaft having the teeth thereof oppositely disposed.

2. In combination with the band wheel shaft of well drilling apparatus having the usual crank for raising and lowering the drilling tools, a band wheel rotatably mounted upon said shaft, a pair of spring pressed ratchet clutches for connecting said band wheel to the shaft having the teeth thereof oppositely disposed and means for simultaneously or independently engaging said clutches.

3. In combination with the band wheel shaft of well drilling apparatus having the usual crank for raising and lowering the drilling tools, a band wheel rotatably mounted upon said shaft, a pair of spring pressed ratchet clutches for connecting said band wheel to the shaft having the teeth thereof oppositely disposed and means for disengaging either of said ratchet clutches.

4. In combination with the band wheel shaft of well drilling apparatus having the usual crank for raising and lowering the drilling tools, a band wheel rotatably mounted upon said shaft and a pair of spring pressed ratchet clutches for connecting said band wheel to the shaft having the teeth thereof oppositely disposed and a control for each clutch for maintaining the clutch in inoperative position against the action of the spring thereof.

In testimony whereof I hereunto affix my signature.

THOMAS S. DIETLE.
